UNITED STATES PATENT OFFICE.

ADAM WASZKIEWICZ, OF NEW YORK, N. Y.

APPARATUS FOR STEAMING CLOTH.

SPECIFICATION forming part of Letters Patent No. 408,775, dated August 13, 1889.

Application filed May 14, 1889. Serial No. 310,723. (No model.)

To all whom it may concern:

Be it known that I, ADAM WASZKIEWICZ, of New York city, New York, have invented an Improved Apparatus for Steaming Cloth, 5 of which the following is a specification.

This invention relates to a machine for steaming or "sponging" cloth. The machine is so constructed that the cloth is steamed while being fed over a straight perforated 10 surface. Thus the cloth will not be unevenly stretched, as is the case if steamed while being wound on rollers.

The invention consists in the various features of improvement more fully pointed out 15 in the claims.

In the accompanying drawings, Figure 1 is a top view of my improved cloth-steaming machine. Fig. 2 is a top view of the steam-box with the muslin partly broken away. 20 Fig. 3 is a cross-section on line xx , Fig. 1; and Fig. 4, an end view of the machine.

The letter a represents a box adapted to be secured to a work-table by screws b , passing through flanges on its bottom plate c . This 25 bottom plate connects with steam-inlet d , while the flat top e of the box is provided with a large number of perforations e' . Over this top a sheet of muslin f is stretched, which is held in place by a frame g , encircling the 30 box. The object of the muslin is to prevent direct action of the steam on the cloth. To a suitable upright h , beyond the front and rear of the box, is secured a rubber cushion i , over which the cloth j to be steamed is passed. 35 A cover k incloses the box and uprights. This cover is provided above the cushions i with corresponding cushions m . The cushions i m , though permitting the introduction and withdrawal of the cloth between them, 40 prevent the escape of steam into the room.

The steam-escape takes place through an elbow-pipe n , connected to the cover and adapted to be coupled to a steam-pipe.

In use the cloth j is placed upon cushions i over box a and the cover k is put in place. 45 Steam is now admitted and the cloth is fed along by a pair of hollow rollers o o , heated by gas and held together by springs p . As the cloth is being fed along, it is subjected to the action of the finely-divided steam. The 50 steam, as will be seen, always acts upon a straight surface of cloth, and thus the cloth will not become unevenly stretched. A uniform result will therefore be obtained and no creases or folds of any kind will be formed. 55

What I claim is—

1. The combination of box a , having a steam-inlet and perforated top e , with cover k , having a steam-outlet, substantially as specified. 60
2. The combination of box a , having steam-inlet and perforated top e , with cover k and uprights h , having cushioned edges for the admission and discharge of the cloth, substantially as specified.

3. The combination of box a , having a steam-inlet and a perforated top, with frame g , holding muslin f , and with cover k , having a steam-outlet, substantially as specified. 65

4. The combination, in a cloth-steaming machine, of the following elements: a steam-box with perforated top, a surrounding muslin-holding frame, a cover having a steam-outlet, cushions between which the cloth is admitted and discharged, and a pair of cloth-feeding heated rollers, substantially as specified. 70 75

ADAM WASZKIEWICZ.
